US00D589703S

(12) **United States Design Patent**
Wenchel et al.

(10) **Patent No.:** **US D589,703 S**
(45) **Date of Patent:** **** Apr. 7, 2009**

(54) **TOOL BIT CONTAINER**

(75) Inventors: **Lauren M. Wenchel**, Bel Air, MD (US);
Gabriel E. Concari, Eldersburg, MD (US)

(73) Assignee: **Black & Decker Inc.**, Newark, DE (US)

(**) Term: **14 Years**

(21) Appl. No.: **29/308,146**

(22) Filed: **May 30, 2008**

(51) LOC (9) Cl. **03-01**

(52) U.S. Cl. **D3/273; D3/905**

(58) **Field of Classification Search** D3/201, D3/203.5–203.6, 206, 225, 228, 230, 260, D3/262, 272–275, 294–295, 302, 315; D9/420, D9/422–424, 430, 432; D19/75, 85–86, D19/90; D99/28, 33; D6/440; 206/315.1, 206/315.11, 349, 372–373, 379
